UNITED STATES PATENT OFFICE.

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

METHOD OF AND MACHINE FOR MAKING HEELS.

Application filed October 18, 1918, Serial No. 258,722. Renewed November 24, 1923.

To all whom it may concern:

Be it known that I, JOHN B. HADAWAY, a citizen of the United States, residing at Swampscott, in the county of Essex and State of Massachusetts, have invented certain Improvements in Methods of and Machines for Making Heels, of which the following description, in connection with the accompanying drawings, is a specification, like reference characters on the drawings indicating like parts in the several figures.

This invention relates to the manufacture of shoe heels and consists in certain improvements in methods and apparatus for effecting economical production of "pasted" heels, or heels, the lifts of which are connected together by adhesives, with or without the aid of heel building nails. A chief function of the adhesive in pasted heels is to prevent checking or opening up of spaces between the lifts as a result of varying moisture conditions to which the heel is subjected in wear. Adhesives which are economical and otherwise desirable to use are pastes that set or dry relatively slowly, and satisfactory results require that the heel be held under pressure while the paste is setting, the usual period of pressure ranging from one-half hour to several hours. It will readily be understood that to hold each heel under pressure for such a period adds materially to the cost of heel manufacture, taxing space and requiring press equipment and labor involving substantial expense. It is particularly burdensome properly to press wedge heels, or those which are higher at the back than at the breast (usually made so by the inclusion of one or more wedge lifts) and which include practically all women's heels.

One important object of this invention is so to improve methods of making heels as to effect economies by reducing the time required for setting the adhesive, thereby lessening substantially the heel pressing equipment and factory space necessary for the production of heels. This is accomplished by expediting the setting of the paste in the freshly built heels. Another important object is to provide a method of pressing wedge heels by which the same press apparatus can be employed for effecting equally efficient pressing of heels of any degree of wedge or no wedge at all. This object is attained by a novel method of stacking wedge heels in a

press. A third object of this invention is to provide mechanism with the aid of which a high degree of heel making efficiency is obtained in the practice of my improved methods.

The fastening of pasted, as well as of dry heels, by one or two headed nails at the time of the heel building operation is generally practised, the nails serving to hold the lifts against slipping one on another while being handled and pressed, before being clinched in the heel compressing operation to restrict expansion of the compressed heel. The first mentioned function of the nail may, in some cases, be dispensed with when my improved methods above referred to are used, but when the nailing is desired for the binding of the compressed heel it is preferably effected by an improved method which constitutes a part of this invention, as does also a novel combination of heel pressing and nailing mechanism herein disclosed for fastening the heel lifts together.

The invention in its various aspects will now be more fully described with the aid of the accompanying drawings and will then be pointed out in the claims.

Figure 1 of the drawings is a side elevation of an illustrative example of the invention;

Figs. 2 and 3 are views on an enlarged scale, showing more clearly details of the heel guide;

Fig. 4 is an enlarged view showing the method of stacking wedged and pitched heels;

Fig. 5 is a front view of the machine shown in the upper portion of Fig. 1;

Fig. 6 is a horizontal, cross-section of the heel holder or upper end of the heel tube;

Fig. 7 shows nail point centering jaws in side elevation and section; and

Fig. 8 shows the same in inverted plan view.

The heel guide in which pasted heels are arranged for pressure and setting in accordance with this invention may be of any suitable construction. The novel guide 10, the construction of which will later be described, is well adapted for the purpose.

In beginning to make heels it is well, though not essential, to use a dummy 12 which fits the guide snugly and has a top face adapted to give support squarely to the lower end of the first heel. The first wedge

heel may be placed in the position of the heel 15. The second heel 16 of like wedge is then placed thereon base to base and turned 180° relatively to heel 15. The outer or top 5 lift ends of the two heels are then in parallelism to receive pressure. Advantageously the next heel 17 is superimposed top lift end down on heel 16 with its breast face over the breast face of heel 16. The adjacent 10 wall of the guide 10 then holds the breast faces in alinement. A heel 18 will then be placed in the same relation to the heel 17 as the heel 16 occupies to the heel 15, that is, base face to base face and turned 180° relatively 15 so that the slant or inclination of the base face of one wedge heel offsets the reverse inclination of the other and presents the opposite ends in parallelism to receive the pressure. It will be noted that by arranging 20 the heels as described and shown in Fig. 4 pitched wedge heels, or those having inclined rear ends, may be so stacked that the top lift end of one heel is opposed to the adjacent top lift end of the next, and the 25 larger base end of one heel is opposed to, or substantially covered by, the adjacent large base end face of the next heel. Thus, when endwise pressure is applied to the column 30 of heels the pressure is distributed evenly over substantially the entire area of every heel face, and each wedged and pitched heel is as evenly pressed as flat, straight heels are when stacked in column. It has been found in practice that wedge heels so 35 stacked with like tapers opposed to each other can be subjected to pressure with substantially no slipping of their inclined base faces upon one another. Attainment of this result is facilitated by abutting the breast 40 faces of the alternate pairs, as 16, 17 and 18, 19 against a wall of the guide, at least in the upper part of the guide 10. The invention is carried out as a continuous operation in practice by pressing the heels intermittently, 45 as each heel is introduced, into a close fitting guide longer than a plurality of heels, the heels being arranged, as they are introduced, in pairs having like wedge and having like end faces in contact, base to 50 base contacting heels being turned 180° relatively to each other.

The setting of pasted heels is expedited according to this invention by subjecting the heels simultaneously to pressure and a circulation of air in contact with them. In the example shown, the heels are intermittently subjected to repeated pressure impulses while being held under continuous pressure, while being subjected to a current 55 of air directed both longitudinally and transversely of the column of heels. This method effects a rapid drying of the heels without the checking of the edges, which has heretofore accompanied rapid drying. 60 The checking is avoided by this invention

by reason of the way in which the application of pressure is co-ordinated with the expedited drying action. The continuing pressure holds the lifts tightly together as the paste is dried and the repeated pressure 70 impulses, which are cumulative in their effect, tend to squeeze out any excess of paste from the freshly pasted heels and take up any shrinkage caused by drying. Advantageously, the freshly pasted heels are subjected to repeated pressures as they are forced down through the close fitting upper portion of the friction guide 10, Figs. 1 and 2, as, for example, the portion extending from the entrance through the first floor. 75 By this time, if heels are introduced at the rate at which they can be built, the paste will have developed considerable adhesiveness. The heels are thus subjected for a time, while under continued pressure, to a 80 cross current of air, the velocity and temperature of which may be varied according to the conditions presented, some pastes and some heel stock being advantageously subjected to a more rapid drying than is beneficial to others. This transverse air current rapidly dries off the surface paste and moisture. Then as the partially set heels progress down through the guide they are subjected to a current of air moving 85 longitudinally of the column for gradually drying them and setting the paste with the accompaniment of pressure and frequent pressure impulses which take up the shrinkage and keep the spaces between the lifts 90 continuously closed. As the heels approach the lower end of the guide, they are subjected to a cross current of fresh, dry air to remove any remaining excess moisture and set the paste firmly while the heels are under 95 pressure. By this invention, a superior pasted heel, which will not check, is produced and the setting of the paste is so expedited that a much shorter friction heel 100 guide 10 may be employed than that heretofore used which commonly extends from the top floor to the basement of a factory and is usually not less than thirty or forty feet 105 long.

When nailed heels are built I find it advantageous to press the heel piles successively into the upper end of the guide with sufficient pressure to force the entire column of heels down the friction guide and to drive the heel-building nail into the pile against 110 the resistance offered by the heel column to further movement down the close fitting guide. Advantageously, the nail or nails are inserted after the application of pressure to force the heel pile into the guide and before it has opportunity to react from the pressure. Also, advantageously, the freshly introduced and nailed heel pile is restrained from reacting from the introducing and nailing pressures. Such reaction after nail- 115

ing has always heretofore been allowed to occur, as I am advised, thereby loosening the lifts, whereas the present method conserves all the compression effected in the nailing, 5 and then accumulates additional pressure as successive heels are superposed in the guide, pressed and nailed.

An apparatus, with the aid of which my 10 improvements in heel making methods may be advantageously practised, is fully shown in the drawings and embodies many valuable features of novelty.

The heel guide 10 comprises two parallel channel bars, see Figs. 2, 5 and 6, each presenting 15 two heel engaging faces forming approximately a right angle to engage the breast face and one side edge of a heel. These are advantageously fluted or channeled, as at 20, to present vertical lines of 20 contact with the column of contained heels and air circulating passages between the ribs. The bars are also preferably recessed or cut away along the angle, as at 22, to permit the entrance of air to the heels and 25 particularly to provide air communication with the exposed surfaces of pitched wedge heels stacked, as shown in the drawings, to present spaces, such as 23. The channel bars have ears 24 to receive the bolts 25, and 30 preferably springs 26, for holding the bars together to constitute a close fitting friction guide for the heels offering such resistance to the introduction of the heel pile, or the passage of the heel column, or both, as to insure 35 a suitable pressing of the heels as they are introduced or are forced through the guide. Preferably, the friction is maintained and, therefore, the pressure upon the heels rendered continuous throughout the 40 column by a plurality of spring couplings 25, 26, and pressure impulses are intermittently transmitted to the entire stack of heels as successive heels are forced into the guide.

Relatively weak springs 28 spread the 45 mouth of the guide 10 when the bolts 25 are loosened and the mouth is flared by beveling the upper end faces of the channel bars to facilitate the introduction of heel piles, as shown at 29. Ratchet teeth 30 are 50 provided which hold a heel pile against the reaction that tends to raise its upper end above the entrance of the guide and loosen the lifts when the introducing and nailing pressures are withdrawn. The outer channel bar ears are slotted at 27, where the bolts 55 engage them, to allow that bar to be adjusted laterally for adapting the guide to different sizes or shapes of heels. The heel guide 10 is secured by bolts 32, passing 60 through its rear channel bars, to the post of the machine and in alinement with the pressing and nailing devices by which heels are successively introduced into the guide, nailed and pressed down through the guide 65 in column formation.

Below the floor the heel guide 10 is enclosed in an air conductor 35, through which a current of dry air is forced from a suitable blower 36, the air passing, if desired, over heating means 38 by which its drying 70 capacity may be increased as required to effect the proper drying of pasted heels passing through the guide under varying weather conditions. Heel making has always been adversely affected by unfavorable 75 weather conditions, as for example, in "dog day" weather it has been impossible to keep up the normal production, and the formation of mold upon heels has been almost inevitable. I consider it very important to 80 provide heel making apparatus with equipment by which adverse atmospheric conditions can be offset and uniform quality and quantity production be maintained at all times. The conductor is constructed and arranged to deliver a cross current of air transversely of the column of green heels. It will be noted that the freshly pasted heels at the upper end of the guide are not subjected to the air current but are allowed to 85 progress under continuous pressure and subjected to intermittent pressure impulses by the means later to be described, while the moisture of the paste penetrates the heel stock and until any excess paste has been 90 squeezed out. The cross currents of air are produced by baffle plates 37 arranged on opposite sides of the conductor 35 and in staggered relation to each other. A lateral outlet conductor 40 is located at or near the head of the air conductor 35 and is provided with a damper 41 to regulate the flow. The effect of the circulation of dry, and preferably warm, air back and forth about the 95 heels is to dry off the excess surface paste rapidly. Within the conductor 35 the air currents have access to the heels through the spaces between the channel bars and the recesses through the bars. In the case of the pitched heels shown in Fig. 4, the air 100 circulates freely in the spaces all around the tapering top lift ends of the heels in the heel guide. The channel bars are formed in sections, and at one or more points within the air conductor, the sections are separated, as at 42, (see Fig. 3) for a distance 105 to allow free access to all parts of the side of the heel normally guided by them. The joints are preferably staggered to afford a 110 guide on one side of the heel column continuously.

The heels or heel piles may be introduced into the heel guide 10 by hand, but I prefer to present heel lifts in properly arranged piles over the mouth of the guide by automatic lift assembling mechanism of the type shown in co-pending application of Ralph C. Simmons, Serial No. 81,405.

The mechanism for pressing the heel piles, or it may be heels that have been built in 130

another apparatus, into the guide 10 comprises a reciprocable plunger 50, having an operative position over the mouth of the guide and a stroke adapted to press a heel pile into the close fitting guide and below the ratchets 30 which co-operate to restrain the heel pile from reacting from the pressure or springing up when the plunger 50 is raised. The plunger, of course, applies at each heel introducing movement a pressure impulse to the entire column of heels in the friction guide 10, and advances the column against the frictional resistance of the guide. This frictional resistance is co-operated with by the ratchets 30 in holding all of the heels including the most freshly pasted one, under unremitting pressure until they are ejected from the lower end of the guide, from whence it is intended that they shall be carried automatically into a heel compressor by a feeding mechanism of the type shown in co-pending application of Thomas Lund, Serial No. 258,849, filed Oct. 19, 1918. It will be understood that neither the feeding and compressing mechanism nor the heel pile assembling mechanism are herein claimed, per se, but only as elements of the combination of mechanisms, here disclosed for the first time in the art, so far as I am aware, for producing from separate lifts pasted, cured and compressed heels. The feeding mechanism preferably includes a conveyor of the link belt type, a portion of which is shown at 60, and each heel pocket in the conveyor has a rear wall or finger 62 arranged to engage the lowermost heel projecting from the guide 10 and co-operate with the opposed wall of the guide in separating that heel from the column if it should have any tendency to adhere to the latter. The heel pressing plunger 50 and the conveyor are operated by connected mechanism in such time relation that a heel pocket stands under the guide 10 when the column of heels is forced downwardly, and the conveyor then advances to cause the finger 62 to force the endmost heel laterally off the column while the column is held by the heel guide. The preservation of the proper time relation between the various units of the system of machines may conveniently be controlled from the indicator lever of the compressing machine, which is actuated once for each reciprocation of the cross head. In the arrangement shown in the drawings, the said lever is connected by a rod to a rock shaft 104 which, in turn, operates a rod 106 connected to trip the one-revolution clutch controlling the actuation of the plunger 50. Another rod 108, also actuated by the rock shaft 104, may be utilized to control a heel building machine for supplying the heel piles automatically to the entrance end of the guide 10, when

such a machine is employed in connection with the system. 65

The described mechanism is organized to assemble and deliver flat or substantially flat heels such as are used largely in men's shoes. For similarly making wedge heels, which are to be stacked by superposing the base face of one heel upon the base face of a heel of like wedge which is turned 180° to present their toplift faces in parallelism for advantageously pressing them in the heel guide, successive heel piles must be differently presented to the heel guide and must be restored to uniform position after delivery from the guide. For this purpose I propose the introduction into the described combination of heel positioning mechanism embodying the invention disclosed in the co-pending application of Fred V. Hart, Serial No. 314,219, filed July 30, 1919. If automatic positioning mechanism for the heels is not provided, the freshly built blanks may be distributed on a support, as indicated at 100, see Fig. 2, in convenient proximity to the upper end of the guide and readily accessible to an operator who may insert the heel into the guide by hand in proper relative arrangement. 80 85 90 95

The heel pressing plunger 50 has a removable foot piece 54 which has an arcuate sliding connection with the head of the plunger to allow it to adapt itself to pressing wedge heels presenting pressure receiving surfaces at different angles to the vertical. The plunger is reciprocated in a vertical guideway in the machine frame by an eccentric on the shaft 55, which is connected to a constantly driven pulley 56 by a one-revolution treadle-controlled clutch and brake which is fully shown and described in my prior Patent No. 1,087,578, granted on my application February 17, 1914. 100 105 110

The mechanism for inserting heel building nails comprises a driver 65 operating through the plunger 50 and having a swinging yoke connection with a driver lever 66 fulcrumed at 67 and lifted by a cam 68 on the shaft 55 against the tension of a driving spring 70. The nails are introduced by suitable automatic feeding mechanism, not shown, through an oblique channel 72, Fig. 5, in the plunger. The nail passage intersects the driver passage at a point such that the descent of the nail is arrested by the side of the driver while both driver and plunger are elevated. When the plunger descends to press the heel pile into the heel guide the nail is carried below the driver and descends into nail point centering jaws 74, Fig. 7, in the lower end of the driver passage. The driver cam and the presser eccentric are timed relatively to effect release of the driver while the plunger is down. The nail 115 120 125

is driven while the heel pile is supported for the nail insertion by the column of heels below it in guide 10. The plunger may be timed to begin to rise before the nail driving movement is completed, the heel pile being held from reacting upwardly by the ratchet faces 30. The nail does not extend fully through the lower lift of the heel pile and offers no obstacle to the separation of 10 the heels from the column by the fingers 62 of conveyer 60.

Having thus described my improved method of making heels and one embodiment of novel and improved mechanism 15 which may advantageously be employed in the practice of the method, what is claimed as new and desired to be secured by Letters Patent of the United States is:

1. That improvement in methods of pressing wedge heels, which consists in superimposing the base face of one heel upon the base face of another heel having the same wedge or taper and which is turned 180 degrees to present its breast face under the 25 rear end of the superposed heel, and applying pressure through the top lift ends of the heels.

2. That improvement in methods of pressing wedge heels, which consists in superimposing the base face of one heel upon the base face of another heel having the same wedge or taper and which is turned 180 degrees to present its breast face under the 30 rear end of the superposed heel, confining 35 the heels thus stacked sufficiently to prevent lateral displacement thereof, and applying pressure through the top lift ends of the heels.

3. That improvement in methods of pressing wedge heels, which consists in superimposing the base face of one heel upon the base face of another heel having the same wedge or taper, and then superimposing a third heel with its top lift end upon the top lift end of the second heel and similarly placing other heels with like ends in contact and with the heels of each pair of base-to-base contacting heels turned 180 degrees 45 relatively to one another, and applying pressure through the ends of the stack thus formed.

4. That improvement in methods of stacking and pressing wedge heels, which consists in placing two heels of like wedge 50 together base to base with one turned 180 degrees relatively to the other to present their outer ends in parallelism to receive the pressure, and applying pressure through the top lift ends of the heels.

5. That improvement in methods of pressing wedge heels, which consists in stacking two freshly pasted heels of like taper so that their outer ends are parallel and applying pressure through said parallel faces.

6. That improvement in methods of mak-

ing wedge heels which consists in pressing the heels intermittently into a close-fitting guide longer than a plurality of the heels, said heels being arranged in the guide in pairs having like wedge and having like 70 end faces in contact, base to base contacting heels being turned 180 degrees relatively to one another.

7. That improvement in methods of pressing pitched heels which consists in superimposing said heels in a close-fitting long friction guide with like ends of the heels together, as large base to large base and small top lift end to small top lift end, whereby 75 each end face of each heel is substantially 80 covered by the similarly sized contacting end of another heel, and applying pressure successively to each heel introduced to force the heels through the friction guide.

8. That improvement in methods of making heels which consists in pressing freshly pasted pitched heels end upon end into a tube which substantially fits the base end of the heel and leaves an air space around the top lift end of each heel, and causing a 90 circulation of air around the heels in said air spaces.

9. That improvement in methods of making heels which consists in pressing freshly pasted, pitched heels end upon end into a 95 guide that is longer than a plurality of heels and frictionally engages the base portions of the heels to produce a resistance against which the heels are subjected to endwise pressure during their progress through the 100 guide, and forcing a circulation of drying air around the portions of the heels not in engagement with the guide.

10. That improvement in methods of making heels which consists in pressing freshly pasted heels end upon end successively into a close-fitting guide that offers a frictional resistance to the passage of the heels sufficient to hold the heels under pressure as they pass through the guide, enclosing a portion of 110 the guide, and forcing a drying current of air longitudinally of the guide in contact with exposed surfaces of the heels.

11. That improvement in methods of making heels which consists in subjecting a freshly pasted heel to a current of drying air while the paste sets and the moisture from the paste dries, and subjecting the heel to repeated pressure impulses while it is drying in the air current.

12. That improvement in methods of making heels which consists in subjecting a freshly pasted heel to a current of drying air while the paste sets and the moisture from the paste dries, and subjecting the heel to unremitting pressure plus repeated pressure impulses to take up any shrinkage during the drying.

13. That improvement in methods of making heels which consists in forcing freshly 130

- pasted heels through a close-fitting guide under pressure while applying a current of drying air to exposed surfaces of the guided heels.
14. That improvement in methods of making heels which consists in subjecting freshly pasted heels to pressure under normal atmospheric conditions for a period during which the heel stack may absorb moisture from the paste and then subjecting the heels for a further period to a current of drying air.
15. That improvement in methods of making heels which consists in subjecting a column of pasted heels to the drying action of an air current while holding them under pressure.
16. That improvement in methods of making heels which consists in subjecting a column of pasted heels to the drying action of an air current while holding them under pressure and increasing the pressure intermittently to take up shrinkage as the heels dry.
17. That improvement in methods of making heels which consists in subjecting a column of pasted heels to the drying action of an air current while holding them under pressure and applying additional pressure impulses while passing the heels through the air current area.
18. That improvement in methods of making heels which consists in subjecting freshly pasted heels to pressure under normal atmospheric conditions for a period, then subjecting the heels to cross and longitudinal currents of drying air while applying pressure to take up any shrinkage and hold the pasted lifts tightly together.
19. That improvement in methods of making heels which consists in pressing a heel into a close-fitting tube, superposing on said heel the lifts of another heel, pressing the said lifts into the tube, and then driving a heel building nail to connect the lifts and render the same separable as a unit from the heel below.
20. That improvement in methods of making heels which consists in pressing a heel into a close-fitting tube, placing another heel over the heel in the tube, pressing the newly placed heel into the mouth of the tube and then nailing the newly placed heel while supporting it against the thrust of the nail driven by the other heel or heels in the tube, the procedure being repeated until the tube is filled and a heel is ejected from the opposite end each time a heel pile is pushed into the mouth of the tube.
21. The combination, with a close-fitting heel guide longer than a plurality of heels, of a presser to force a heel pile into the guide, and means arranged to drive a heel building nail down into the heel pile after it has been forced into the guide.
22. The combination, with a holder for a heel pile, of means to press the heel pile down into the holder, and means arranged to drive a nail down into the pressed heel pile.
23. The combination, with a heel holder, of a vertically movable presser to press a heel pile in the holder, and means to drive a heel building nail into the heel pile, said means including a nail driver movable in and independent of the presser, and a nail guide arranged to direct a nail against the driver in the presser when the presser is raised and to guide the nail below the driver when the presser descends.
24. The combination, with a reciprocable heel presser having a driver passage and a nail passage extending obliquely to and joining the driver passage more than a nail's length above the lower end of the presser, of a nail driver, said parts being constructed and arranged to allow nails fed into the nail passage to be stopped against the driver while the presser is up and to descend into the driver passage when the presser is depressed.
25. The combination, with an air conductor, of a heel guide extending through the conductor and adapted to hold a column of heels with more or less of their edge faces exposed, and means for inducing a circulation of air through the conductor.
26. A heel guide comprising two channel bars, each presenting substantially right angular faces for engaging heels on the breast and one side, and means for holding the channel bars in heel guiding relation, each of said bars being formed to present to the heel faces a plurality of narrow contacting areas separated by air circulating passages.
27. A heel guide comprising two channel bars, each presenting substantially right angular faces for engaging heels on the breast and one side, and means for holding the channel bars in heel guiding relation, said bars being cut away along the angle for a portion of their length to expose the contained heels to the air.
28. The combination, with an air conductor, of a heel guide extending longitudinally through the conductor and constructed and arranged to hold a column of heels with more or less of their edges exposed, and means to produce cross currents of air at a portion of the heel column where the heel edges are exposed.
29. The combination, in an apparatus for setting pasted heels, of a heel guide longer than a plurality of heels and formed to expose a portion of the edges of the heels, an air conductor surrounding a lower portion of the heel guide and arranged to direct a cross current at one or more points intersecting the column of heels in the guide, and means for inducing a current of air in the conductor.

30. The combination, in an apparatus for setting pasted heels, of a heel guide longer than a plurality of heels and formed to expose a portion of the edges of the heels, an air conductor surrounding a lower portion of the heel guide and having an outlet at one side opposite a point where heels in the guide are exposed, and a head closing the conductor above the outlet to require the air to pass out transversely of the heel column.

31. A heel guide comprising two channel bars, each presenting substantially right angular faces for engaging heels on a breast corner and one side, and means for holding the channel bars in heel guiding relation, said bars having ratchet teeth on upper portions of the heel engaging walls, to restrain retrograde movement of heels introduced into the guide.

32. Apparatus for making pasted heels having, in combination, a heel curing guide through which heels are made to progress in column formation under pressure holding the lifts firmly together for the setting of the paste, said guide being constructed and arranged to permit access of air to the edge faces of the heels, an air conductor enclosing the heel guide for a portion of its length and regulatable means for varying the drying action of the air in the conductor to permit the production of uniformly cured heels under varying weather conditions.

33. Apparatus for making pasted heels having, in combination, means for effecting the progress of heels under pressure successively through an air conductor and constructed and arranged to expose the edges of the heels to the action of air currents, an air conductor constructed and arranged to enclose the heels for an extended period during such progress, and means to induce air currents through said conductor and in contact with the heels under pressure.

34. Apparatus for making pasted heels having, in combination, means for effecting the progress of heels under pressure successively through an air conductor and constructed and arranged to expose the edges of the heels to the action of air currents, an air conductor constructed and arranged to enclose the heels for an extended period during such progress, and means for inducing air currents through said conductor and in contact with the heels under pressure including cross currents directed transversely of the line of heels.

35. Apparatus for making pasted heels having, in combination, means for effecting the progress of heels under pressure successively through an air conductor and constructed and arranged to expose the edges of the heels to the action of air currents, an air conductor constructed and arranged to enclose the heels for an extended period dur-

ing such progress, means for inducing air currents through said conductor, and regulatable means to vary the drying action of the air currents to offset adverse weather conditions which retard the curing of the heels.

36. Apparatus for making pasted heels having, in combination, a heel curing guide through which heels are made to progress in column formation under pressure, holding the lifts firmly together for the setting of the paste, said guide comprising co-operating side members formed in sections, and an air conductor enclosing the guide for a portion of its length, the sections of one of said guide members being separated for a substantial distance at a point within the conductor to permit free access of the air to the surfaces of the heels normally in contact with said guide member.

37. Apparatus for making pasted heels having, in combination, a heel curing guide through which heels are made to progress in column formation under pressure, holding the lifts firmly together for the setting of the paste, said guide comprising co-operating side members one of which is formed in sections which are separated for a substantial distance at a point below the heel receiving portion of the guide, to expose to the air the surface of the heels normally in contact with that member of the guide, said heels being supported at such point by the other side member of the guide.

38. Apparatus for making pasted heels having, in combination, a long, close-fitting friction guide for the heels, mechanism for pressing a heel pile into the guide, mechanism for driving a building nail into the heel pile, means for subjecting the heels to the paste drying action of air currents to cure them for compressing while they are moved step by step through the guide by the introduction of additional heels, and a conveyor for receiving the cured heels from the guide.

39. Apparatus for making pasted heels having, in combination, a long, close-fitting friction guide to receive a heel pile, and mechanism for pressing the heel pile into the guide and nailing the heel pile after it is in the upper end of the guide.

40. Apparatus for making pasted heels having, in combination, a long, close fitting guide, means for pressing heels into the guide and, by operating upon successive heels, for advancing the heels through the guide under pressure while the paste sets, a conveyor to receive the heels from the guide, and means operated by the conveyor to discharge the endmost heel from the heel column at the lower end of the guide in a position to be received by the conveyor.

41. Apparatus for making pasted heels having, in combination, a long, close-fitting

heel guide, means for pressing heels into the guide and, by operating on successive heels, for advancing the heels through the guide under pressure while the paste sets, and a moving conveyor to receive the heels and convey them away from the guide.

42. Apparatus for making pasted heels having, in combination, a long, close-fitting guide, means for pressing heels into the guide and, by operating on successive heels, for advancing the heels through the guide under pressure while the paste sets, a conveyor to receive the heels from the guide, and means to dislodge the endmost heel from the heel column at the lower end of the guide in a position to be received by the conveyor.

43. Apparatus for making pasted heels having, in combination, a long, close-fitting heel guide, means for pressing heels into the guide and, by operating on successive heels, for advancing the heels through the guide under pressure while the paste sets, and means co-operating with the lower end portion of the heel guide to separate each heel from the column of heels in the guide.

44. Apparatus for making pasted heels having, in combination, a holder into which assembled heel lifts are pressed, means for nailing the lifts together to form a heel, a

moving conveyor, and means for pressing the heels through the holder and delivering them to the conveyor.

45. A heel machine having, in combination, two mechanisms independently driven from their source of power for performing successive operations upon heels, means controlled by one of said mechanisms for transferring the heels from the first mechanism to the second mechanism, and means for controlling the operation of one of said mechanisms from the other to secure proper time relation of the two mechanisms with the transferring means.

46. A machine for operating upon heels having, in combination, a heel-press and a heel-compressor for performing successive operations upon heels, said press and compressor being independently driven from their source of power, an interconnected mechanism for synchronizing the operation of the compressor and the press to secure proper time relation between them, and a conveyor operated in proper time relation with said press and compressor for transferring heels from said press to said compressor.

In testimony whereof I have signed my name to this specification.

JOHN B. HADAWAY.
